ABSTRACT: This invention is directed to humidifiers of commercial manufacture which are placed in the plenum chamber of a warm air furnace, with the emphasis on the quick and easy removal of the evaporator pan when it becomes caked with mineral deposits which result from the evaporation of water, without benefit of removal or total disassembly of the humidifier from the furnace.

PATENTED FEB 23 1971

3,565,053

FIG. 1

FIG. 2

INVENTOR

BY *LAWRENCE W. HAMILTON*

ROBERT H. ELLIOTT

EXPENDABLE HUMIDIFIER TRAY

It is therefore a primary object of the present invention to provide a disposable humidifier tray or pan which generally conforms to the configuration of the structure now employed that minimizes the now existant problem of cleaning.

Another object of the invention is the provision of a throwaway humidifier tray which is durable and relatively inexpensive to manufacture.

Still another object of this invention is the provision of a humidifier tray which is free standing with an integral flange thereon for cooperation with the pan support means.

Another object of the invention is the provision of a laminated humidifier tray, wherein the upper or topmost tray is torn off and discarded each time mineral deposits effect the efficiency of the humidifier unit.

Still another object of the present invention is the provision of a humidified residence, wherein the humidifier service can be maintained by the home owner or other unskilled help, thus reducing the overall cost of operation and maintenance.

The above and other objects of this invention can be accomplished by the provision of a commercial humidifier having a controlled level water supply for the evaporator pan which is separate and removable from the humidifier assembly proper that provides the support frame means for the said humidifier evaporator pan, the frame support means may be pivotal if consistent with the design of the particular humidifier used, however the support means need not be a frame, but could of course be a pan of predetermined configuration and into which the humidifier evaporator liner would be placed and when sufficient mineral deposits accumulate, the liner or other removable tray is merely removed and discarded and replaced with another of similar kind in a minimum of time and at a modest expense.

Other objects of this invention will appear in the following description and appended claims, reference being had to the accompanying drawings which form a part of this specification, wherein like reference characters designate corresponding parts in the several views.

IN THE DRAWINGS

FIG. 1 illustrates a side elevation of a commercial humidifier which embodies the teachings of the present invention.

FIG. 2 is a plan view of the structure shown in FIG. 1 of the drawings.

FIG. 3 shows a free standing laminated evaporator pan.

FIG. 4 teaches the use of inexpensive throwaway fittings secured to the evaporator pan, for humidifiers having a below surface water ingress.

Before explaining the present invention in detail, it is to be understood that the invention is not limited in its application to the details of construction and arrangement of parts illustrated in the accompanying drawings, since the invention is capable of other embodiments and for being practiced or carried out in various ways. Also, it is to be understood that the phraseology or terminology employed herein is for the purpose of description and not of limitation.

Looking now at the drawings, specifically FIG. 1, it will be observed that a humidifier assembly 10 has been installed in the plenum chamber P of a warm air furnace. This assembly 60 consists of a water valve 14 having a water supply 12. The water valve being actuated by the pivotal displacement of the

evaporator pan 16 which is supported in the pivotal frame member 18 that circumscribes the evaporator pan 16. The liquid level in the evaporator pan can however be controlled in many ways, as for example as illustrated in U.S. Pat. Nos. 5 2,565,210 issued to N. J. Dovilis, Aug. 21, 1951, the U.S. Pat. No. 2,654,362 to Scharf, dated Oct. 6, 1953, or U.S. Pat. No. 3,087,485 to M.A. Powers dated Apr. 30, 1963, or any number of others, without departing from the spirit or scope of the present invention.

10 It will be readily apparent that when a disposable pan or tray is positioned within the confines of the frame 18 that it can be rapidly removed and replaced with another pan or tray of a like variety in a minimum of time and little or no effort without getting dirty. This is not possible to accomplish today, 15 since for the most part the evaporator tray is integral with the humidifier assembly and can only be cleaned by removal of the complete unit from the furnace. Thus a dirty, time consuming and unpleasant job results, the postponement of which results in a health hazard, as well as the rapid deterioration of 20 the furniture within the heated home. Thus the advantages of a free standing or supported evaporator pan are self evident.

The support frame 18 may be of any desired design or cross-sectional configuration, such as a vertically disposed rectangular member, or a flanged member of generally L-shaped configuration as illustrated in FIGS. 1 and 2 respectively. The flange 22 on the evaporator pan cooperates with the flange on the support member to prevent the pan from dropping through.

25 FIG. 3 of the drawings illustrates a nested and laminated evaporator pan construction similar to that shown in connection with FIGS. 1 and 2, however, with this construction, it is only necessary to remove the topmost layer of the laminate to effect a cleaning of the humidifier pan. In this embodiment, four laminates A,B,C and D are deposited in the support pan 30 SP.

35 In FIG. 4 of the drawings, a single free standing pan is illustrated, wherein fittings 32 are secured thereto so that the water ingress can be accomplished below the maintained water level in the evaporator pan. These of course could be 40 made of plastic and fitted with O-rings to prevent leaks.

I claim:

1. In a commercially available humidifier having a controlled level water supply, the combination of:
45 a removable free standing evaporator pan having a flange thereon;
support means circumscribing said evaporator pan and cooperable with said removable evaporator pan and flange thereon; and
said cooperable support means maintaining said evaporator pan in the proper position to control the water level therein.
2. In a commercially available humidifier having a controlled level water supply, the combination of:
50 a removable evaporator pan having a flange thereon;
support means in the form of an endless ring which circumscribes the said flanged evaporator pan and engages same; and
said cooperable support means are pivotal and separate from said evaporator pan, while maintaining said evaporator pan in the proper position to control the water level therein.
